[57] CLAIM

The ornamental design for a golf iron club head, as shown and described.

DESCRIPTION

FIG. 1 is a plan view of a golf iron club head, showing my new design;

FIG. 2 is a front elevational view thereof;

FIG. 3 is a bottom view thereof;

FIG. 4 is a rear elevational view thereof;

FIG. 5 is a left side elevational view thereof; and

FIG. 6 is a right side elevational view thereof.

The broken line showing of a fragmented shaft is for illustrative purposes only.
